ABSTRACT

New antibiotic, steffimycin B produced by the controlled fermentation of the new microorganism *Streptomyces elgreteus* Dietz sp. n. in an aqueous nutrient medium. Steffimycin B is active against Gram-positive bacteria and can be used in various environments to eradicate or control such bacteria.

**ANTIBIOTIC STEFFIMYCIN B AND PROCESS FOR
THE PREPARATION THEREOF**

BRIEF SUMMARY OF THE INVENTION

The novel compound of the invention, steffimycin B (U-40615) is obtained by culturing *Streptomyces elgreteus* sp. n., NRRL 5634, in an aqueous nutrient medium. It is an acidic compound and has the property of adversely affecting the growth of Gram-positive bacteria, for example, *Bacillus subtilis*, *Bacillus cereus*, *Staphylococcus aureus*, *Streptococcus hemolyticus*, *Streptococcus faecalis*, and *Diplococcus pneumoniae*. Accordingly, steffimycin B can be used alone or in combination with other antibiotic agents to prevent the growth of or reduce the number of bacteria, as disclosed above, in various environments.

DETAILED DESCRIPTION OF THE INVENTION

**CHEMICAL AND PHYSICAL PROPERTIES OF
STEFFIMYCIN B**

CHL,1 Elemental Analysis: Calc'd. for C₂₉H₃₂O₁₃

C, 59.18; H, 5.48; O, 35.34

Found: C, 58.68; H, 5.58; O, 35.74 (diff.)

Molecular Weight: 588 (determined by mass spectrometry).

Specific Rotation: [α]_D²⁵ = +94° (c, 2, CHCl₃)

Ultraviolet Absorption Spectra:

In ethanol : λ max. at 234 μ (a = 47.3)
sh at 254 μ (a = 36.9)
sh at 274 μ (a = 33.3)

In 0.1N alcoholic KOH : λ max. at 223 μ (a = 53.7)
sh at 259 μ (a = 45.0)

In 0.1N alcoholic HCl : λ max. at 234 μ (a = 46.7)
sh at 254 μ (a = 36.6)
sh at 274 μ (a = 33.0)

Infrared Absorption Spectra: Infrared absorption spectrum of steffimycin B suspended in a mineral oil mull is reproduced in FIG. 1 of the drawings. Steffimycin B shows peaks at the following wave lengths expressed in reciprocal centimeters:

Band Frequency (cm ⁻¹)	Intensity	Band Frequency (cm ⁻¹)	Intensity
3610 (sh)	W	1230	S
3550 (sh)	M	1200	S
3530	S	1185	S
3410	M	1165	S
3070 (sh)	W	1135	S
2930 (oil)	S	1110	S
2880 (oil)	S	1087	S
1717 (sh)	M	1077	S
1710	S	1056	S
1674	M	1040	S
1625	S	1015	S
1603	S	1004	S

687	M		

Infrared band intensities, throughout this disclosure, are indicated as "S", "M", and "W", respectively, and are approximated in terms of the backgrounds in the vicinity of the bands. An "S" band is of the same order of intensity as the strongest in the spectrum; "M" bands are between $\frac{1}{3}$ and $\frac{2}{3}$ as intense as the strongest band; and, "W" bands are less than $\frac{1}{3}$ as intense as the strongest band. These estimates are made on the basis of a percent transmission scale. "sh" denotes a shoulder.

Nuclear Magnetic Resonance (NMR): Steffimycin B has a characteristic NMR spectrum as shown in FIG. 2 of the accompanying drawings. The NMR spectrum was recorded on a Varian A-60 spectrometer on a solution (ca. 0.5 ml., ca. 15 percent concentration) of the sample of steffimycin B in deuterio-chloroform (CDCl₃). The spectrum was calibrated against internal tetramethylsilane and the precision of the Δν was $> \pm 1$ c.p.s. Frequencies were recorded in c.p.s. downfield from tetramethylsilane.

Papergram: Steffimycin B is distinguished from steffimycin by a characteristic papergram R, as shown in FIG. 3 of the accompanying drawings.

Mobile phase: Benzene 1 part; methanol 1 part; water 2 parts (use only upper phase for development)

Matrix: Schleicher and Scheull 589 Blue Ribbon paper

Detecting Organism: *S. lutea*

Antibacterial Activity Of Steffimycin B

Test Microorganism	Minimum Inhibitory Concentration in mcg./ml.	5
<i>Staphylococcus aureus</i>	4.0	
<i>Streptococcus hemolyticus</i>	7.8 ± 4.0	
<i>Streptococcus faecalis</i>	7.8

<i>Diplococcus pneumoniae</i>	1.0	

The tube dilution assay procedure was conducted 15 with the medium BHI (Brain Heart Infusion Broth, Difco, Detroit, Mich.). Assay tubes (13 mm. × 100 mm.) were prepared in the customary manner as set out in Snell, E. E., *Vitamin Methods*, Volume 1, Academic Press, Inc., New York 1950, p. 327. Test organisms grown for 18 hours at 37° C. were used to inoculate the test medium. The assays were read at 17 hours. 20

THE MICROORGANISM

The microorganism used for the production of the antibiotic of the subject invention has been named *Streptomyces elgretensis* sp. n. One of its strain characteristics is the production of steffimycin B. A subculture of the living organism was deposited and can be obtained from the permanent collection of the Northern Utilization and Research Division, Agricultural Research Service, U. S. Department of Agriculture, Peoria, Illinois, U.S.A. Its accession number in this repository is NRRL 5634. 30

The microorganism of this invention was studied and characterized by Alma Dietz of the Upjohn Research Laboratories. 35

DESCRIPTION OF THE MICROORGANISM

Taxonomy: *Streptomyces elgretensis* Dietz sp. n.

Color characteristics: Aerial growth lavender-gray to gray-pink. Melanin-negative. Appearance on Ektachrome is given in Table 1. Reference color characteristics are given in Table 2. The culture may be placed in the Gray (GY) or Red (R) color groups of Tresner and Backus (Tresner, H. D., and E. J. Backus. 1963. System of color wheels for streptomyces taxonomy. *Appl. Microbiol.* 11:335-338).

Microscopic characteristics: Sporophores long, straight (RF) in the sense of Pridham et al. (Pridham, T. G., C. W. Hesseltine, and R. G. Benedict. 1958. A guide for the classification of streptomyces according to selected groups. Placement of strains in morphological sections. *Appl. Microbiol.* 6:52-79). Spores, examined with the transmission electron microscope, appeared long (often rectangular) with flattened ends and smooth surface by direct examination; by examination of carbon replica preparations, the spore surface appears to have peeled and looks curly. The spore surface by direct examination with the scanning electron microscope was hairy with a wooly appearance. Electron microscope procedures were those of Dietz and Mathews (Dietz, A., and J. Mathews. 1962. Taxonomy by carbon replication. I. An examination of

Streptomyces hygroscopicus. *Appl. Microbiol.* 10:258-263; see also *Appl. Microbiol.* 21:526-533).

Cultural and biochemical characteristics: Cultural and biochemical characteristics are described in Table 3.

Carbon utilization: In the synthetic medium of Pridham and Gottlieb (Pridham, T. G., and D. Gottlieb. 1948. The utilization of carbon compounds by some Actinomycetales as an aid for species determination. *J. Bacteriol.* 56:107-114), *S. elgretensis* had poor growth on the control (basal medium without added carbon compound), D-xylose, L-arabinose, lactose, raffinose, inulin, dulcitol, D-mannitol, D-sorbitol, salicin, sodium acetate, and sodium citrate; moderate growth on rhamnose, D-fructose, maltose, sucrose, dextrin, and sodium succinate; good growth on D-galactose, D-glucose, D-mannose, cellobiose, soluble starch, glycerol, and inositol; no growth on phenol, cresol, sodium formate, sodium oxalate, sodium tartrate, and sodium salicylate. In the synthetic medium of Shirling and Gottlieb (Shirling, E. B., and D. Gottlieb. 1966. Methods for characterization of *Streptomyces* species. *Int. J. Syst. Bacteriol.* 16:313-340), the culture grew poorly on the negative control (synthetic medium without added carbon compound) and on D-xylose and D-mannitol; well on the positive control (synthetic medium with D-glucose), and inositol, and moderately well on D-fructose and rhamnose. The culture did not grow on D-arabinose, sucrose, raffinose, or cellulose.

Temperature: *S. elgretensis* had good aerial growth on Bennett's agar at 18°C-28°C and on maltose-tryptone agar at 24°C-28°C. The culture had fair vegetative growth on these media at 37°C and no growth in 24 hours at 45°C and 55°C.

Antibiotic-producing properties: The culture produces steffimycin B and some steffisburgensimycin (U. S. Pat No. 3,309,273), also known as steffimycin.

Source: Soil.

Type culture: *Streptomyces elgretensis* sp. n. UC 5453.

DISCUSSION

A new soil isolate capable of producing the antibiotic steffimycin has been characterized and determined to be a new streptomyces species. The new culture is distinctly different from the steffimycin-producer, *Streptomyces steffisburgensis* (Dietz, A. 1967. *Streptomyces steffisburgensis* sp. n. *J. Bacteriol.* 94:2022-2026). The culture has lavender-gray to gray-pink aerial growth, is melanin negative, solubilizes tyrosine, does not solubilize xanthine, and has straight sporophores bearing long spores with smooth to curly to hairy surface appearance. *S. steffisburgensis* has gray aerial growth, is melanin positive, does not solubilize tyrosine, solubilizes xanthine, and has short, straight, open spiral to spiral sporophores bearing short spiny (Dietz, A. 1967. *Streptomyces steffisburgensis* sp. n. *J. Bacteriol.* 94:2022-2026) or warty (Dietz, A., and J. Mathews. 1970. Classification of *Streptomyces* spores into five groups. *Appl. Microbiol.* 21:527-533) spores. The new soil isolate differs from cultures characterized in Waksman (Waksman, S. A. 1961. The Actinomycetes, Vol. 2. Classification, Iden-

tification, and Descriptions of Genera and Species. The Williams & Wilkins Co., Baltimore), Hutter (Hutter, R. 1967. Systematik der Streptomyces. S. Karger, Basel. 382p), and Shirling and Gottlieb (Shirling, E. B., and D. Gottlieb. 1968. Cooperative description of type cultures of *Streptomyces*. II. Species descriptions from first study. Int. J. Syst. Bacteriol. 18:69-189. Shirling, E. B., and D. Gottlieb. 1968. Cooperative description of type cultures of *Streptomyces*. III. Additional species descriptions from first and second studies. Int. J. Syst. Bacteriol. 18:279-399. Shirling, E. B., and D. Gottlieb. 1969. Cooperative description of type cultures of *Streptomyces*. IV. Species descriptions from the second, third and fourth studies. Int. J. Syst. Bacteriol. 19:391-512) and from cultures in The Upjohn Culture Collection. Therefore, it is proposed that the culture characterized herein be designated *Streptomyces elgretus* Dietz sp. n. It is understood that this type species is also to be considered the type variety in accordance with Rule 7 of the International Code of Nomenclature of Bacteria (INTERNATIONAL CODE OF NOMENCLATURE OF BACTERIA. 1966. Edited by the Editorial Board of the Judicial Commission of the

10
15
20

International Committee on Nomenclature of Bacteria. Intern. J. System. Bacteriol. 16:459-490).

The characteristics of *Streptomyces elgretus* NRRL 5634, are given in the following tables:

Table 1 - Appearance of *Streptomyces elgretus* on Ektachrome

Table 2 - Reference Color Characteristics of *Streptomyces elgretus*

Table 3 - Cultural and Biochemical Characteristics of *S. elgretus*

The new compound of the invention is produced when the elaborating organism is grown in an aqueous nutrient medium under submerged aerobic conditions. It is to be understood also that for the preparation of limited amounts surface cultures and bottles can be employed. The organism is grown in a nutrient medium containing a carbon source, for example, an assimilable carbohydrate, and a nitrogen source, for example, an assimilable nitrogen compound or proteinaceous material. Preferred carbon sources include glucose, brown sugar, sucrose, glycerol, starch, cornstarch, lactose, dextrin, molasses, and the like. Preferred nitrogen sources include cornsteep liquor, yeast, autolyzed brewer's yeast with milk solids, soybean meal, cottonseed meal, cornmeal, milk solids, pancreatic digest of casein, distillers' solids, animal peptone liquors, meat and bone scraps, and the like. Combinations of these carbon and nitrogen sources can be used advantageously. Trace metals, for example, zinc, magnesium, cobalt, iron, and the like, need not be added to the fermentation media since tap water and unpurified ingredients are used as components of the medium.

Production of the compounds of the invention can be effected at any temperature conducive to satisfactory growth of the microorganism, for example, between about 18° and 40° C., and preferably between 20° and 32° C. Ordinarily, optimum production of the compounds is obtained in about 2 to 10 days. The medium normally remains basic during the fermentation. The final pH is dependent, in part, on the buffers present, if any, and in part on the initial pH of the culture medium.

When growth is carried out in large vessels and tanks, it is preferable to use the vegetative form, rather than the spore form, of the microorganism for inoculation to avoid a pronounced lag in the production of the new compounds and the attendant inefficient utilization of

the equipment. Accordingly, it is desirable to produce a vegetative inoculum in a nutrient broth culture by inoculating this broth culture with an aliquot from a soil or a slant culture. When a young, active vegetative inoculum has thus been secured it is transferred aseptically to large vessels or tanks. The medium in which the vegetative inoculum is produced can be the same as, or different from, that utilized for the production of the new compound, as long as it is such that a good growth of the microorganism is obtained.

Steffimycin B forms salts with alkali metals, alkaline earth metals, and amines. Metal salts can be prepared by dissolving steffimycin B in methanol, adding a dilute metal base until the pH of the solution is about 7 to 8, and freeze drying the solution to provide a dried residue consisting of the steffimycin B metal salt. Steffimycin B metal salts include the sodium, potassium, and calcium salts. Amine salts of steffimycin B, including those with organic bases, such as primary, secondary, and tertiary, mono-, di-, and polyamines also can be formed using the above-described rather commonly employed procedures. Other salts are obtained with therapeutic effective bases which impart additional therapeutic effects thereto. Such bases are, for example, the purine bases such as theophyllin, theobromin, caffeine, or derivatives of such purine bases; antihistaminic bases which are capable of forming salts with weak acids; pyridine compounds such as nicotinic acid amide, isonicotinic acid hydrazide, and the like; phenylalkylamines such as adrenaline, ephedrine, and the like; choline, and others.

Steffimycin B and its salts are active against *Staphylococcus aureus* and *Streptococcus faecalis* and can be used to disinfect washed and stacked food utensils contaminated with these bacteria; they can also be used as disinfectants on various dental and medical

equipment contaminated with *Staphylococcus aureus*. Further, since steffimycin B and its salts are active against *Streptococcus hemolyticus*, they can be used to disinfect instruments, utensils or surfaces where the inactivation of this microorganism is desirable.

The new compound of the invention is an acidic chemical compound. It is soluble in halogenated hydrocarbons and lower alcohols. It is relatively insoluble in hydrocarbons and water.

A variety of procedures can be employed in the isolation and purification of steffimycin B, for example, solvent extraction, partition chromatography, silica gel chromatography, liquid-liquid distribution in a Craig apparatus, absorption on resins, and crystallization from solvents. Solvent extraction procedures are preferred for commercial recovery inasmuch as they are less time consuming and less expensive.

In a preferred recovery process, steffimycin B is recovered from its culture medium by separation of the mycelia and undissolved solids by conventional means, such as by filtration or centrifugation. The antibiotic is then removed from the filtered or centrifuged broth by extraction. For the extraction of steffimycin B from the filtered broth, water-immiscible organic solvents in which it is soluble, for example, 1-butanol, methyl ethyl ketone, benzene, and methylene chloride (preferred) can be used. Advantageously, the extraction is carried on after the filtered beer is adjusted to a pH of about 2 to 4 with a mineral acid. The methylene chloride extractions are combined and evaporated to dryness under vacuum.

Steffimycin B can be recovered in the pure form from a methylene chloride extract, as described above, by use of silica gel chromatography.

Alternatively, steffimycin B can be recovered from fermentation filtered broth by use of a resin comprising a non-ionic macro porous copolymer of styrene cross-linked with divinylbenzene. Suitable resins are Amberlite XAD-1 and XAD-2 disclosed in U. S. Pat. No. 3,515,717. The resin is eluted with an organic or aqueous organic solvent in which the sorbed antibiotic is soluble.

An alternative purification procedure involves subjecting a crude preparation of steffimycin B to successive crystallizations from lower alcohols, for example, methanol, ethanol, propanol, and the like; chlorinated hydrocarbons, for example, chloroform, methylene chloride, and the like; hydrocarbon solvents, for example, pentane, hexane, heptane, and the like; or admixtures of any of these.

It is to be understood that the microbiological process disclosed herein, though described in detail with particular references to the novel microorganism *Streptomyces elgreteus* sp. n., NRRL 5634, is not limited to this particular microorganism fully described by the cultural characteristics disclosed herein. It is intended that this invention also include other strains or mutants of the said microorganism which can be produced by procedures well known in the art, for example, by subjecting the novel microorganism to x-ray or ultraviolet radiation, nitrogen mustard, phage exposure, and the like.

Hereinafter are described non-limiting examples of the process and products of the subject invention. All percentages are by weight and all solvent mixture proportions are by volume unless otherwise noted.

Example 1

Part A. Fermentation

Mycelium and/or spores from a slant of *Streptomyces elgreteus* sp. n., NRRL 5634, are used to inoculate a series of 500-ml. Erlenmeyer flasks each containing 100 ml. of seed medium consisting of the following ingredients:

10	Glucose monohydrate	25 gm./l.
	Pharmamedia*	25 gm./l.
	Tap water q.s.	1 liter

*Pharmamedia is an industrial grade of cottonseed flour produced by Trader's Oil Co., Ft. Worth, Texas.

15 The presterilization of the seed medium is 7.2. The seed is grown for three days at 28° C. on a Gump rotary shaker operating at 250 r.p.m.

16 The fermentation proper is carried out in the medium 20 of the following composition:

Blackstrap molasses	25 gm./l.
Yellow cornmeal	20 gm./l.
Pharmamedia	15 gm./l.

25 The medium is adjusted to pH 7.2 with 50 percent sodium hydroxide, distributed in 100 ml. volumes/500 ml. Erlenmeyer flasks and sterilized at 121° C. for 25 minutes. The inoculated flasks (5 percent inoculum by 30 volume) are incubated at 28° C. on a Gump rotary shaker operating at 250 r.p.m. A representative fermentation has the following assays:

35	Day	Assay (BU/ml.)	
		1	2
	1	0	
	2		4
	3		7
	4		16
	5		13

40

The assay was an agar disc-plate assay against the microorganism *Sarcina lutea*. The assay against *Sarcina lutea* is conducted on agar buffered to pH 7.4 with pH 7.4 phosphate buffer. A unit volume (0.08 ml.) of solution containing the substance to be assayed is placed on a 12.7 mm. paper disc which is then placed on a Penassay Seed Agar (Difco), 1 mm. deep, plate seeded with the assay organism. The agar plate is then incubated for 16-18 hours at 32° C. A biounit (BU) is defined as the concentration of the antibiotic which gives a 20 mm. zone of inhibition under the standard assay conditions. Thus, if for example a fermentation beer has to be diluted 1/100 to give a 20 mm. zone of inhibition, the potency of such beer is 100 BU per ml.

55 Part B. Recovery

Whole fermentation beer, obtained as described above, is filtered using diatomaceous earth as a filter aid. The filter cake is washed with water. The wash is combined with the clear beer and the combined solution is extracted twice with an equal volume of methylene chloride. The methylene chloride extracts are combined and evaporated to dryness at less than 40° C. under vacuum. The potencies of the clear broth, spent broth and extracts are determined by dip spotting (12 mm. discs) on *S. lutea* seeded agar. (The potency of the preparation is determined by preparing a 50 mcg./ml. solution in CH_2Cl_2 and making serial dilutions to

5γ/ml., 80 mcl. are applied to 12 mm. paper discs and spotted on *S. lutea* seeded agar. The dilution giving a 20 mm. zone of inhibition determines the number of biounits.) The composition of the preparation is determined by thin layer chromatography (tlc) on silica gel using a mobile phase consisting of the following solvents:

CH₂Cl₂—30 parts
Acetone—10 parts
Hexane—3 parts
Methanol—2 parts

The chromatography column is wet packed (using the mobile phase described above) with 50 to 100 gm. of silica gel H (Merck/gm. of steffimycin B preparation to be processed. After the column has settled, a solution of the steffimycin B preparation in a minimum volume of CH₂Cl₂ is charged onto the column. The column is eluted with the mobile phase, described above, at a flow rate of approximately 10 ml./min. During the elution, a number of colored bands develop. The fraction containing the first faint yellow band is discarded and the fraction containing the first deep orange band is collected. This fraction is cut so that none of the second red-orange band which contains steffimycin is collected. The purity of steffimycin B is checked by tlc on 15
silica gel using the above mobile phase. The purified steffimycin B, thus obtained, does not contain any other colored (or fluorescent) material by tlc.

Steffimycin B is obtained in its pure crystalline form by subjecting the fraction containing steffimycin B, as 20
described above, to successive crystallization procedures from methanol.

We claim:

1. Steffimycin B, a compound which:
  - a. is effective in inhibiting the growth of various 25
Gram-positive bacteria;
  - b. has an optical rotation $[\alpha]_D^{25} = +94^\circ$ (c, 2, CHCl₃);

c. has a characteristic ultraviolet absorption spectrum as follows:

5	In ethanol	: λ max. at 234 μ (a = 47.3) sh at 254 μ (a = 36.9) sh at 274 μ (a = 33.3)
	In 0.1N alcoholic KOH	: λ max. at 233 μ (a = 53.7) sh at 259 μ (a = 45.0)
	In 0.1N alcoholic HCl	: λ max. at 234 μ (a = 46.7) sh at 254 μ (a = 36.6) sh at 274 μ (a = 33.0);

- d. has a characteristic infrared absorption spectrum in mineral oil mull as reproduced in FIG. 1 of the drawings;
- e. has the following elemental analyses: C, 58.68; H, 5.58; O, 35.74;
- f. has a characteristic nuclear magnetic resonance spectrum as shown in FIG. 2 of the drawings;
- g. has a characteristic *R_f* in the chromatographic system, as shown in FIG. 3, which differentiates it from steffimycin; and
- h. as a molecular weight of 588 as determined by mass spectrometry, or non-toxic base addition salts thereof.

2. A process for making steffimycin B, the compound of claim 1, which comprises cultivating *Streptomyces elgretetus* sp. n., having the identifying characteristics of NRRL 5634, in an aqueous nutrient medium under aerobic conditions until substantial antibiotic activity is imparted to said medium by the production of steffimycin B.

3. A process, according to claim 2, wherein said aqueous nutrient medium contains a source of assimilable carbohydrate and assimilable nitrogen.

4. A process, according to claim 2, wherein said steffimycin B is isolated from the fermentation broth.

UNITED STATES PATENT OFFICE
CERTIFICATE OF CORRECTION

Patent No. 3,794,721

Dated February 26, 1974

Inventor(s) Thomas F. Brodasky, Fritz Reusser

It is certified that error appears in the above-identified patent
and that said Letters Patent are hereby corrected as shown below:

Column 1, line 24, for "CHL, 1 Elemental" read --
Elemental --. Column 2, line 65, for "Scheull" read --
Schuell --. Column 3, lines 5-6, for "Con-Inhibitory"
read -- Concentration --; Column 3, line 52, for "Dridham"
read -- Pridham --. Column 4, line 18, for "D-galac-tose"
read -- D-galactose --; Column 4, line 32, for "O-arabinose"
read -- L-arabinose --; Column 4, line 65, for "Appl,"
read -- Appl. --. Column 5, table 2, for "P tan, russet
tan" read -- tan, russet tan --. Column 11, line 14, for
"(Merck/gm." read -- (Merck)/gm. --.

Signed and sealed this 10th day of September 1974.
